(57) **CLAIM**

The ornamental design for a gas cylinder valve, as shown and described.

DESCRIPTION

FIG. 1 is a perspective view of a gas cylinder valve showing our new design;

FIG. 2 is a front view thereof;

FIG. 3 is a back view thereof;

FIG. 4 is an enlarged left view thereof;

FIG. 5 is an enlarged right view thereof;

FIG. 6 is a top view thereof;

FIG. 7 is a bottom view thereof; and,

FIG. 8 is an enlarged view of the encircled area 8 of FIG. 2.

The evenly spaced broken lines depict portions of the gas cylinder valve that form no part of the claimed design. The long-dash-dot broken lines denote the boundaries of the enlarged detail view areas and form no part of the claimed design.
